The ornamental design for a robotic pool cleaner caddy cover, as shown and described.

DESCRIPTION

FIG. 1 is a front, right and top perspective view of a robotic pool cleaner caddy cover, showing my design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof.

FIG. 7 is a bottom plan view thereof; and,

FIG. 8 is a partial enlarged view of an area labeled 8 in FIG. 1 comprising an adjusting buckle.

The broken lines shown in the drawings are included for the purpose of illustrating portions of the robotic pool cleaner caddy cover that form no part of the claimed design.

The dash-dot lines shown in FIGS. 1 and 8 illustrate the boundary of the enlarged views and form no part of the claimed design.
